CLAIM

The ornamental design for a display screen or portion thereof with a graphical user interface of an electronic device, as shown and described.

DESCRIPTION

FIG. 1 is a front view of a first embodiment of a display screen or portion thereof with a graphical user interface of an electronic device.

FIG. 2 is a front view of a second embodiment of a display screen or portion thereof with a graphical user interface of an electronic device.

FIG. 3 is a front view of FIG. 1 shown in an alternate environment; and,

FIG. 4 is a front view of FIG. 2 shown in an alternate environment.

The broken lines showing an electronic device display screen or portion thereof and elements of the graphical user interface represent environment and form no part of the claimed design.

1 Claim, 4 Drawing Sheets
